United States Patent Office.

WILLIAM R. KING, OF WASHINGTON, DISTRICT OF COLUMBIA.

Letters Patent No. 99,323, dated February 1, 1870.

IMPROVEMENT IN MACHINE FOR MOVING BOATS ON CANALS.

The Schedule referred to in these Letters Patent and making part of the same

I, WILLIAM R. KING, of the United States Corps of Engineers, now residing in the city of Washington, District of Columbia, have invented a Machine for Applying Motive-Power to Boats, (on canals and elsewhere,) of which the following is a specification.

The object of my invention is to secure a practical and economical application of steam or other motor to the propulsion of boats, or other vessels, upon canals, certain river-channels, or any other suitable water-way.

I will assume as already existing, but as forming no part of my invention—

First, a canal or any other suitable channel or water-way.

Second, a boat or vessel, of any desired form or dimensions.

Third, a steam-engine, or other suitable motor, located upon any convenient part of the boat.

My invention consists of two principal parts, (see annexed drawing,) viz.:

First, an axle, D E, connected with the motor C, by belts and pulleys, cog-wheels, or in any other practicable manner, and carrying a driving-wheel at the end E. This axle is placed preferably near the bow of the boat, and nearly at right angles to a vertical plane through its keel, though it is not limited to any particular direction or position. It has a telescopic or sliding joint, J, which may be allowed to slide freely for a certain distance, or it may be firmly clamped, as circumstances may require. The connection of this axle with the boat, at D, is made by a universal joint, K, which will allow any desired horizontal traverse to the axle, and will accommodate any accidental difference of level between the deck of the boat and the rail, without bringing an undue strain upon the bearing. The direction of the axle, with respect to the boat, is maintained by the brace G H. The drive-wheel E may be provided with ledges or projections on its circumference, (similar to those upon a mowing-machine drive-wheel,) and allowed to roll upon the tow-path, or it may be grooved, and caused to roll upon a rail, as hereinafter described. In the former case, the wheel and axle will constitute the essential parts of my invention; that is, the wheel and axle being revolved by the motor, the boat will be propelled along the canal.

I prefer, however, to add a second principal part, as follows:

Second, a fixed rail, A B, parallel to the side of the canal, and at a convenient distance from the outer side of the boat. This rail may be made of a light pattern of railroad-iron, of cast-iron, or of wood, and should be supported at intervals by vertical or inclined posts *p p*, of wood or iron, firmly secured in the bank or

wall of the canal. The grooved wheel E, if made of sufficient weight to give the necessary tractile force upon the rail, would draw the boat, but it will be found best to add the extra grooved wheel F, which runs under the rail, the axle of this wheel and that of the wheel E being drawn together by the strain upon the brace G H applied through the knee-joint E G F.

It will be seen that by making the angle at E less than the limiting angle of friction, the force of traction will increase faster than the strain upon the brace, or, what is the same thing, the resistance of the boat, and the driving-wheel E will not, therefore, slip on the rail, however great the resistance of the boat may be.

The wheels E and F may, if desired, be connected by cogs, which will double the force of traction, and the angles at E and F may be made twice the limiting angle of friction, without reducing the force of traction below what is required to draw the boat.

When the motor is stopped or reversed, the knee-joint will release the wheels from the rails, and they may be swung aboard the boat, for the purpose of entering locks, or passing other boats, (in case the canal has a rail upon one side only.)

To enable boats to run in either direction upon the same rail, the drive-wheel may be shifted from side to side of the boat by swinging the axle one hundred and eighty degrees, horizontally about the pivot K, and making the proper adjustments of the brace G H, and the belt, or other connection with the motor.

In order to facilitate this last operation, the pivot K may have two sockets, which will bring the pulley in the centre line of the boat, whichever side the drive-wheel may occupy.

Claims.

What I claim as my invention, and desire to secure by Letters Patent, is—

1. The combination of the axle D E, knee-joint E G F, wheels E and F, and brace G H, by means of which the resistance of the boat is made to compress the wheels against the rail A B, and thus secure the tractile force required to propel the boat, substantially as an for the purposes set forth.

2. The combination of the knee-joint E G F, wheels E and F, rail A B, and brace G H, substantially as and for the purposes set forth.

3. The flexible and extensible connection of the axle with the boat, by means of the universal joint K and the telescopic joint J, substantially as and for the purposes set forth.
